United States Patent Office

Des. 208,043
Patented July 4, 1967

208,043

BARBECUE ACCESSORY CADDY OR SIMILAR ARTICLE

Robert A. Clark, Allentown, Pa., assignor to Caloric Corporation, Topton, Pa., a corporation of Pennsylvania

Filed Nov. 16, 1965, Ser. No. 88,118

Term of patent 14 years

(Cl. D81—10)

FIG. 1 is a perspective view of a barbecue accessory caddy or similar article embodying the design.

FIG. 2 is a top plan view showing the same.

FIG. 3 is a side elevational view of the same.

FIG. 4 is an end elevational view of the same.

The dotted line showing of implements is for illustrative purposes only.

I claim:

The ornamental design for a barbecue accessory caddy or similar article, as shown and described.
